Atty.*

D. J. OWEN, OF SPRINGVILLE, PENNSYLVANIA.

Letters Patent No. 85,025, dated December 15, 1868.

WAGON-BRAKE.

The Schedule referred to in these Letters Patent and making part of the same.

To all whom it may concern:

Be it known that I, D. J. OWEN, of Springville, county of Susquehanna, State of Pennsylvania, have invented a new and improved Brake for Wagons; and I hereby declare the following to be a full, clear, and exact description thereof, which will enable those skilled in the art to make and use the same, reference being had to the accompanying drawings, making a part of this specification, in which—

Figure 1 is a transverse vertical section of a wagon, with my improved brake attached, through line *xx*, fig. 2.

Figure 2 is a side elevation of the same.

Figure 3 is a top view of the same.

Similar letters of reference indicate corresponding parts.

My invention relates to brakes for wagons; and

It consists in the combination of a wedge-formed rubber, with suitable devices for regulating the degree of pressure upon the wheels.

As the construction of none of the parts of a wagon is claimed, with the exception of the devices for regulating the brake-blocks, I enter into a minute description of those parts only which are directly connected with such devices, and of the devices themselves.

A, in the drawings, are the wheels of the wagon.

B are the axles.

C is the reach.

D are the rear hounds.

E are the forward hounds.

F is the tongue.

G are the standards.

H is the bed.

H' is the ratchet.

I is the brake-beam or support, which is secured to the hounds, and to the reach, by being notched in its lower surface, so as to fit thereon, and is held in position by means of screws or bolts, which pass through the beam and hounds at their point of junction. In the upper surface of this beam a groove is formed, for the reception of the shaft K, into which said shaft is secured by eye-bolts passing through said beam.

K is a shaft, which is placed in the groove in the brake-beam or support, as above indicated, to the outer ends of which cranks L L', are applied, which cranks receive and carry upon their wrist-pins brake-

blocks, which blocks are so arranged that, when placed in position to be acted upon by the wheels, they will be forced down between the brake-beam or support and such wheels, and thus made to resist the motion of such wheels, or of the wagon, in proportion to the load carried, and the inclination of the descent made.

L L' are the cranks above described.

M are the brake-blocks or rubbers. They are wedge-shaped.

N is a vertical arm, constructed at right angles with the brake-shaft, and upon it, to the top of which connecting-rod O is secured.

O is the connecting-rod, secured in any convenient manner to the arm N and to the hand-lever P.

P is the hand-lever, which communicates motion to the shaft, and the cranks thereon, by means of connecting-rod O and vertical arm N.

From the foregoing description, it is evident that a brake of this kind is self-acting, and that it requires no exertion of strength on the part of the driver to put the brake-blocks in position for action, or to withdraw them. The rubber may be easily lowered by drawing the hand-lever back, to suit the plane descended or the load carried. The pressure had may be very slight, or sufficiently strong to bring the wheels to a deadlock, by lowering the rubber until its head rests between the support and the wheels.

I do not claim, as my invention, a wedge-shaped brake-block or rubber; but

I do claim—

1. The combination of the fixed support I with the shaft K, cranks L L', and brake-blocks M, substantially as shown and described.

2. The arrangement of hand-lever P, connecting-rod O; and vertical arm N, with reference to the shaft K and crank L L', substantially as shown and described.

In testimony whereof, I have signed my name to this specification, in the presence of two subscribing witnesses.

D. J. OWEN.
